DESIGN.

—o—

W. E. SAYERS.

CARPET.

No. 17,663.

Patented Aug. 23, 1887.

UNITED STATES PATENT OFFICE.

WILLIAM E. SAYERS, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 17,663, dated August 23, 1887.

Application filed July 21, 1887. Serial No. 244,937. Term of patent 3½ years.

To all whom it may concern:

Be it known that I, WILLIAM E. SAYERS, of New York city, in the county and State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design is composed of a succession of 15 fan-shaped figures having an irregular coral-like outline, the figures being somewhat open at the lower and central parts and solid and continuous elsewhere.

What I claim as new, and desire to secure by 20 Letters Patent, is—

The design for carpets, consisting of the design substantially as shown.

WM. E. SAYERS.
